(57) **CLAIM**

The ornamental design for hand sign, as shown and described.

DESCRIPTION

FIG. 1 is a right side elevational view of a first embodiment of a left-hand hand sign according to the invention;

FIG. 2 is a left side elevational view of the left-hand hand sign of FIG. 1;

FIG. 3 is an enlarged bottom-side elevational view of the left-hand hand sign of FIG. 1;

FIG. 4 is an enlarged top- side elevational view of the left-hand hand sign of FIG. 1;

FIG. 5 is an enlarged front-side elevational view of the left-hand hand sign of FIG. 1;

FIG. 6 is an enlarged rear-side elevational view of the left-hand hand sign of FIG. 1;

FIG. 7 is a perspective view from the rear of the right-side of the left-hand hand sign of FIG. 1;

FIG. 8 is a perspective view from the rear of left side of the left-hand hand sign of FIG. 1;

FIG. 9 is a left side elevational view of a second embodiment of a right-hand hand sign according to the invention;

FIG. 10 is a right side elevational view of the right-hand hand sign of FIG. 9;

FIG. 11 is an enlarged bottom-side elevational view of the right-hand hand sign of FIG. 9;

FIG. 12 is an enlarged top- side elevational view of the right-hand hand sign of FIG. 9;

FIG. 13 is an enlarged front-side elevational view from the front of the right-hand hand sign of FIG. 9;

FIG. 14 is an enlarged rear-side elevational view of the right-hand hand sign of FIG. 9;

FIG. 15 is a perspective view from the rear of the left-side of the right-hand hand sign of FIG. 9; and,

FIG. 16. is a perspective view from the rear of right side of the right-hand hand sign of FIG. 9.
